J. MOSSMAN;
REMOVABLE PROTECTIVE CAP FOR KNITTING NEEDLES AND THE LIKE.
APPLICATION FILED NOV. 9, 1918.

1,376,964.

Patented May 3, 1921.

Inventor:
James Moosman,
By John Elias Jones,
Attorney.

UNITED STATES PATENT OFFICE.

JAMES MOSSMAN, OF CINCINNATI, OHIO.

REMOVABLE PROTECTING-CAP FOR KNITTING-NEEDLES AND THE LIKE.

1,376,964.

Specification of Letters Patent.

Patented May 3, 1921.

Application filed November 9, 1918. Serial No. 261,861.

To all whom it may concern:

Be it known that I, JAMES MOSSMAN, a citizen of the United States of America, and a resident of Cincinnati, in the county of 5 Hamilton and State of Ohio, have invented a certain new and useful Improvement in Removable Protecting-Caps for Knitting-Needles and the like, of which the following is a specification.

10 This invention relates to point protectors or guard-caps for knitting-needles, pencils, hat-pins and the like, and comprehending thereunder single-point celluloid sweater-needles as well as double-point steel hosiery-
15 needles; and the prime object thereof is to provide a device of said character, in either single or multiple form to suit the purpose desired, that will protect not only the point of the needle when not in knitting use but, 20 also, hold the needle in place against accidental removal or dislodgment from the yarn in the partly made-up or unfinished article, to otherwise cause lost stitches, at the time when the knitting operation is not 25 going on, or when the said unfinished article is being handled or while laid away, so that the work will not be disturbed or upset at the point where laid by or discontinued, and, also, when used as a hat-pin 30 point protector it will prevent the pin from accidental withdrawal or loss, or the point coming in damaging and painful contact with the fingers of the wearer or with other persons or objects, especially with the eyes 35 or other like vital parts of those near the hat wearer, or when the pins are put away in vases, jars, boxes or elsewhere out of active use. The device is still further useful in protecting the point of the knitting-needle 40 from bending or wearing contact when not in use, which is quite an important feature in preserving intact the desired points suited to the many uses of the device.

The details of structure of the protector-
45 cap will be fully hereinafter described in connection with the accompanying sheet of drawings, in which—

Figure 1 is a plan view of the finished knitting-needle protector-cap structure embodying my invention herein, it being shown 50 in multiple adapted to the customary series or set of four double-pointed needles that are used ordinarily in the knitting of hosiery, netting and the like;

55 Fig. 2, a longitudinal section taken across the device, on the dotted-line 2, 2, of Fig. 1,

but including a series or set of needles in place therein;

Fig. 3, a longitudinal cross-section of one of my needle protector-cap units, showing 60 the point of a knitting-needle in seated and protected place therein;

Fig. 4, a side elevation of a single unit protector-cap especially adapted to knitted sweater work, showing a needle with its 65 point in protected place therein;

Fig. 5, a diagram of the blank strip from which the multiple form of my protector-cap device herein is struck-up and made; and—
70

Fig. 6, a sectional view, similar to Fig. 3, but of a modification containing a rubber or like cushioned lining in the cavity for receiving and protecting the point of the needle, and preventing its shifting or slipping 75 from place within its seat, the needle, however, being omitted in this view.

7 indicates a sweater knitting-needle usually made of celluloid and having a blunt head 8 at one end, with a medium point 9 at 80 its opposite end, Fig. 4 showing it in engagement with stitches 10 of the work 11, the latter being but a fragment of the progressing sweater fabric.

12 indicates the preferred form of metal 85 strip or blank from which my device herein in multiple is made. This strip is of rectangular form and has rows of open key-hole shape slots 13 at its opposite ends and a transverse row of cavities or circular recesses 14 made in the center of the blank, as best shown in Fig. 5. This blank is bent over centrally into the finished protector-cap product that has a resilient bow ligament or central portion 15 and integral 90 clamping-arms 16, the latter being under spring-tension imparted by said resilient bow-ligament.

The clamping-arms 16 are in associated pairs that duly register along the multiple 100 form of device seen in Figs. 1 and 2 and are thereby adapted to engage the pointed ends of four needles used in knitting hosiery, such, more particularly, as men's socks. If needles with both ends pointed be used, a 105 multiple device such as that seen in Figs. 1 and 2 is applied to the opposite ends of the said four needles when collectively brought together and thus the needle points themselves, the person of the user, the container bag or work receptacle, and surrounding objects are all protected simultaneously,
110

and the said needles are properly held in place in the work where left off in the progress thereof.

The outer ends of the clamping-arms 16 are 5 made concavo-convex, as best shown in Fig. 2, so as to snugly engage the round surface of the needles, and it will be further seen, in both Figs. 3 and 6, that the extreme outer ends of said clamping-arms are flared outwardly at 17 to more readily guide the points of the needles into place between said clamping-arms, the latter exerting the desired frictional spring-tension on the needles and preventing the accidental dislodgment of the protector-caps when in use. 15

The cavities or depressions 14 serve as seats for the needle points and ordinarily prevent the latter shifting laterally when the caps are in place for protector use. To still further prevent the accidental shifting of the needle points from the seats 14 I provide the spring bow-portion 15 of the respective protector-caps with a washer or lining 18 of rubber or the like, an opening 19 being made 20 in such washer for the entrance of the needle point in seating the latter in the cavity 14 without danger of bending or blunting or 25 other ordinary injury in such seating. The

said opening 19 is preferably made tapered, as best shown in Fig. 6, for facilitating the 30 said entrance of the needle point into seating place in the cavity 14. The washer is best held in place in the bow-portion of the protector-cap by means of cement to prevent ordinary dislodgment. 35

I claim:—

A point-protecting device or a protector-cap for knitting-needles comprising a pair of arms having resilient clamping-jaws the latter concavo-convex in cross-section and 40 also having outwardly-flared outer ends, an imperforate spring bow-portion integrally-connecting the inner ends of said arms under resilient tension, a central outwardly-extending socket provided in the said spring 45 bow-portion and adapted to seat the knitting-needle point, and a resilient lining provided in said socketed bow-portion and having a central wide-mouthed tapered opening to said socket in the bow-portion to frictionally-seat said point free from shifting or accidental withdrawal and, also, whereby the said point is protected from bending or blunting in seating, substantially as 50 shown and described.

JAMES MOSSMAN.
